UNITED STATES PATENT OFFICE.

THURE DAHL, OF NEW YORK, N. Y.

DESIGN FOR A LIGHT RECEPTACLE FOR LIGHTING FIXTURES.

Application filed February 10, 1921. Serial No. 444,036. Term of patent 3½ years.

To all whom it may concern:

Be it known that I, THURE DAHL, a subject of the King of Sweden, residing at New York city, in the county of New York and State of New York, have invented a new, original, and ornamental Design for Light Receptacles for Lighting Fixtures, of which the following is a specification, reference being had to the accompanying drawing, forming part thereof.

The figure is a side view of a light receptacle for lighting fixtures showing my new design.

I claim:

The ornamental design for a light receptacle for lighting fixtures as shown.

THURE DAHL.
